UNITED STATES PATENT OFFICE.

RUDOLF VON SOTHEN, OF BERLIN, GERMANY.

TYPE-WRITING MACHINE.

No. 824,597.

Specification of Letters Patent.

Patented June 26, 1906.

Application filed January 8, 1905. Serial No. 239,482.

To all whom it may concern:

Be it known that I, RUDOLF VON SOTHEN, a subject of the King of Prussia, German Emperor, and a resident of 77 Sebastianstrasse, Berlin, Kingdom of Prussia, German Empire, have invented certain new and useful Improvements in Type-Writing Machines, of which the following is an exact specification.

My invention relates to improvements in type-writing machines, and has for its purpose to facilitate the setting in of formularies or the like to be written upon.

In the machines hitherto used the carriage must be raised and moved sideward or machine parts must be removed in order to be able to precisely set in the paper so that the types strike the beginning of the positions in the formulary or the like. By these manipulations much inconvenience and loss of time are caused. In writing upon papers in unequal vertical-line distances after having cut out the usual line-set mechanism it often happens that the paper was turned over its lower edge, so that it fell out of the machine, together with the copies lying underneath. It was then difficult to again place these papers into the machine for finishing the writing. Furthermore, at changing formularies the writer could not at once see upon which numbers of the scale the tabulator-stops had to be set in farther, which of the columns of the formulary had to be filled in in black or other color, and whether any copies or how many of them were to be left without prices by placing small paper strips between the sheets of paper. Furthermore, in filling out some of a series of positions printed below each other—as, for instance, with railway-stations, wage-lists, or the like—it often happens with type-writing machines now in use that after having raised the carriage for setting in the position desired the latter was turned too far or it could not be seen whether this position desired was at the beginning or at the end of the series of positions. All these disadvantages are avoided by my new attachment to the type-writing machine, consisting in a cylindrical pattern and an index, which pattern is perfectly visible to the writer and contains all indications necessary to fill out formularies with the usual type-writing machine with covered writing. "Machines with covered writing" means such machines in which the printed or written lettering in part cannot be

seen temporarily or in such machines in which a part of the blank paper set out in the machine is covered. The pattern is so arranged on the machine that it can be turned simultaneously with and independently from the writing-roller of the machine and is adapted to control the paper as soon as set out in the machine in horizontal and vertical direction.

A device has become known in which a scale-cylinder numbered on its periphery is arranged upon the axle of the platen or writing-roller and indicates the consecutive numbers and position of the type-written lines. The numbers upon the scale-cylinders must all be of equal distances corresponding to the line distance of the type-writer. Now it is a fact that the printed matter on formularies, bills, invoices, and the like are not so exactly printed that the distances between the several lines to be written upon are permanently equal to the line distance desired or a multiple thereof; but if such formularies show any irregularities in the distances of their lines the scale-cylinder, above indicated, can no more be used, as its line-numbers are no more exactly in conformity to the lines of the formulary. For this reason this device works perfectly unsatisfactory and is only of limited use.

In my device I have dispensed with the condition that the lines of the printed matter of the formulary are of a regular distance, and, furthermore, my device can be used to put in any point of the paper not only in vertical, but also in horizontal direction. For this purpose I use a cylindrical pattern, upon the circumference of which letters, numbers *f* *i* for controlling the known front scale on the type-writer carriage, and marks are provided which individually correspond to the original formulary to be written upon. This pattern is so arranged on the type-writer that the covered part of the formulary placed in the machine can be visibly controlled in horizontal and vertical direction without the necessity of raising the carriage.

With the aid of my device the type-writer enables the operator to perform the greatest quantity of any work in the shortest time possible, without the necessity of learning numbers by heart and any other inconveniences, works perfectly satisfactorily and becomes of unlimited use.

In order that my invention may be fully understood, it will now be described with reference to the accompanying drawings, in which—

- 5 Figure 1 is a front view of a type-writing machine fitted out with one convenient form of my improvement. Fig. 2 is a top view of the machine shown in Fig. 1. Figs. 3 to 7 show modified forms of patterns and of connecting the same to the writing-roller of a type-writing machine. Fig. 8 illustrates a pattern composed of several parts. Fig. 9 shows the lettering of a formulary to be placed upon a pattern. Fig. 10 is a diagram.
- 15 In the drawings, *a* is the platen or writing-roller of a type-writing machine mounted in the carriage-frame *b*. This latter runs, by means of rollers *d*, upon convenient rails carried by the machine-frame *e*.
- 20 *f* is a front scale fastened to the carriage, and *g* is an index secured to the stationary frame *e*.
- 25 *h* is a ratchet-wheel fastened upon the writing-roller axle. *h'* is a ratchet by means of which the writing-roller can be turned forward, thereby setting in the lines to be written upon. This line-setting mechanism *h h'* can be cut out, so that by means of a small hand-wheel *i* the writing-roller can be turned
- 30 independently of the step-by-step line-set mechanism. At the left-hand side of the writing-roller *a* a pattern-roller *k* is mounted. This roller *k* is provided with a sleeve *k'*, fitting over the end of the writing-roller axle *l* and fastened thereon by means of a set-screw *k*².
- 35 *m* is a cylindrical pattern which in the present form consists of a hollow cylinder which is placed upon the pattern-roller *k* and is held in position thereto by a set-pin *n*, fastened to the right-hand sleeve *o* of the roller *k*. Inside the hollow pattern-roller *k* a lever *p* is fastened, which is pressed outward by a spring *q*. The lever *p* carries two pins *p' p*², *p'* projecting through a corresponding bore in *k*, whereas the pin *p*² projects over the outside edge of the pattern-roller *k*, thereby preventing the cylindrical pattern *m* from being drawn off. The pin *p*² presses against the
- 40 inner surface of the pattern *m*, thereby helping to keep the pattern in position. If *m* shall be drawn off from the pattern cylinder *k*, the lever *p* is pressed down by pressing upon the outside free lever end, thereby moving
- 45 down the pins *p' p*² and allowing a drawing-off of the pattern *m*. *r* is an arm fastened to the carriage-frame *b* and carrying an index *s*, held in position upon *r* by convenient means.
- 50 The use of the device is as follows: If, for instance, a formulary, blank, or the like carrying the print shown in Fig. 9 shall be filled out, a pattern carrying upon its circumference the same wording or some characteristic words of the print or a part thereof is to
- 55 be used; but besides this the pattern carries all indications necessary to perfectly fill out the formulary without being obliged to raise the carriage of the type-writing machine and this, if necessary, independently from the usual line-set mechanism and the pitch of the set-wheel of the writing-roller. So, for instance, the formulary, Fig. 9, indicates by the numbers "65 14 50 40 11" upon which division-line of the carriage-front scale *f* the index *g* must show, so that the types strike the desired place on the corresponding horizontal lines. The pattern, further, carries a set-mark *t*. After the pattern has been placed upon the pattern-roller *k* and fixed thereon by the means above described the paper-roller, together with the pattern-roller, is so placed that the index *s* is opposite to the horizontal position of the set-mark. The latter is so placed upon the pattern that it is now only necessary to loosely place the formulary to be written upon from above upon the pressure-rollers *u* and to advance the paper by turning the writing-roller by means of the hand-wheel *i* in order to bring the formulary upon the writing-roller in a position exactly corresponding with that of the pattern. Now if, for instance, the date shall be written behind the word "Albany" the pattern is, together with the writing-roller, so placed that the index *s* shows upon the horizontal line whereupon "Albany" is printed. Now the carriage is moved sidewise so the index *g* is opposite to the division-line "65" of the front scale *f*, and the filling out of the date can now be effected by pressing down the corresponding keys of the keyboard *K*. After this has been done the pattern-roller and writing-roller are further advanced, so that the index *s* is opposite to the horizontal line upon which "Messrs." is standing. The pattern shows behind this word the number "14," indicating that the carriage shall be moved so far, that the index *g* is opposite to the division-line "14" of the front scale *f*. If this has been done, the address can at once be written behind the word "Messrs." without being obliged to raise the carriage. In the same manner the formulary can be set in in order to fill out the free spaces of the formulary behind the words "Per," "For," "To," and so on. The pattern-print shown in Fig. 9 further indicates that the tabulator-stops "9 15 74" shall be used. Furthermore, the writer finds upon the pattern the remark "Two copies," thereby being instructed that he has to make two copies of the formulary. The numbers "9 15 74" indicating the numbers of the tabulator-stops to be used, may be written upon the pattern in other color than the numbers "65 14," &c., indicating the division-lines of the front scale *f* to be used. For this purpose a polychrome ribbon may be made use of, which can in known manner be so shifted that the writing is effected in red or black or any other color.

The form of my patterns, as well as the manner of arranging the same with regard to the writing-roller, may be varied according to the work to be done.

5 Fig. 3 shows a pattern-roller m' , consisting of a solid roller, upon the outer circumference of which the pattern is provided. This roller m' has a sleeve k' and can be placed thereby upon the free outside end of the writing-roller axle l' and fastened thereon by means of the set-screw k^2 . By loosening the screw the pattern-roller m' can be moved independently from the platen, or it can be taken off and substituted, if desired, by another 15 pattern-roller carrying another pattern upon its circumference.

Fig. 4 shows a pattern m^2 , arranged by the side of the writing-roller a inside the carriage-frame b , upon the outside of which the axle l 20 carries a small thumb-roller i' for turning the writing-roller, together with the pattern-roller m^2 . Before the pattern m^2 an adjustable index s is again arranged upon the frame b .

25 Fig. 5 shows a writing-roller, in connection with two pattern-rollers $m'm'$, arranged within the carriage-frame b . Fig. 7 also shows a writing-roller a and two patterns $m'm'$, arranged upon the same axle, one of the patterns m' being arranged within the frame b , the other at the right-hand side outside this frame. The inside patterns in Figs. 4 and 7 30 may consist of hollow cylinders detachably placed upon the axle of the writing-rollers a , or if the writing-roller a is sufficiently long the pattern may be directly placed upon the circumference of the writing-roller itself.

35 Fig. 8 shows a pattern-roller consisting of several parts I II III IV V. These parts can 40 be separately drawn off of the roller proper and placed in other succession than shown in Fig. 8, or one of them may be substituted by another part.

If long formularies shall be filled out—for 45 instance, formularies with railway-stations, which are put below each other—and the length of which is greater than the circumference of the writing-roller, a spiral pattern, as shown in Fig. 6, may be made use of.

50 The pattern of Fig. 6 shows a number of stations written upon the pattern so as to form a spiral thereupon. With this pattern a formulary having the three-fold length of the circumference of the writing-roller a can, for instance, be filled out. The different parts of 55 the spiral pattern may be differently colored, so as to distinguish each from the other, or for filling out long formularies a gearing may be arranged between the pattern and the writing-roller so that the writing-roller makes, for instance, two or three revolutions for each revolution of the pattern. Of course in 60 both of these cases the pattern-carrier or the pattern-roller, upon which the pattern is placed, must be arranged on a separate shaft,

situated either in alignment with the axis of the plate or on a shaft situated at a convenient place behind or before the axle of the writing-roller and a gearing having the required ratio of transmission is connected to the axle of the platen and the pattern-roller. In this case the vertical distances of the horizontal lines of the pattern would be correspondingly reduced. This gear can be so constructed that the ratio of transmission between pattern and writing roller can be changed. 75

The use of the pattern-rollers shown in Figs. 3 to 8 is of course the same as that described above with regard to the pattern 80 shown in Figs 1 and 2.

The device shown in Fig. 5, in which two pattern-rollers are arranged upon the axle of the writing-roller, is for special purposes, in which always the same formularies are to be 85 written on. Both rollers $m'm'$ may be simultaneously used, or the one of the rollers may be used for writing one kind of formularies, bills, or the like and the other pattern-roller for a second kind of formularies. The spiral 90 pattern of Fig. 6 is used for long formularies, the length of which is greater than one circumference of the writing-roller. During the use the index s may be left stationary, or after one turn of the spiral pattern has been 95 used the indicator s may be so displaced that it shows upon the lettering of the second or third turn of the spiral pattern, or the indicating end of the index may be enlarged to an 100 indicating edge of sufficient length parallel to the pattern; but such a displacing is not absolutely necessary; as the lines upon which the lettering is placed are drawn through the whole length of the pattern.

The lettering of the patterns is of course 105 displaced with regard to the print of the formulary placed upon the writing-roller, as the indicator s is about in the height of the pattern-axle, (indicated in Fig. 10 by w'), whereas the types strike the formulary, for instance, at the 110 lowest place of the writing-roller, (indicated in Fig. 10 at w .) The pattern may also be provided upon a strip of paper and glued upon the circumference of the free end of the paper-roller. In order to prevent that the lettering 115 of the pattern being damaged, the same may be provided with a translucent cover consisting of glass, celluloid, or gelatin.

My new device may be attached to any one 120 of the known type-writing systems.

The pattern, which may be of any required diameter and length, may be engraved or written directly upon the circumference of the cylindrical writing-roller, or a whole 125 formulary equal to that to be filled out may be directly fastened upon the pattern-roller, or, as done in the pattern of Fig. 2, only several characteristic words of the formulary or other characteristic indications for setting in all vertical and horizontal points necessary to 130

fill out a corresponding formulary, letter, blank, or the like may be put upon the circumference of the pattern-roller. The patterns can easily be made by the writer, and if finished are ready for use at every time for filling out corresponding formularies from the beginning to the end without the necessity of raising the machine-carriage.

The patterns arranged within the carriage-frame at the side of the writing-roller are in general not exchangeable or machine parts must first be removed in order to substitute it by another pattern-roller. Such arrangements are therefore especially suitable for such machines which only serve special purposes where always the same pattern is used, and therefore need not be substituted by other patterns.

Having thus fully described the nature of my invention, what I desire to secure by Letters Patent of the United States, is—

1. In a type-writing machine, the combination with a platen, of a cylindrical pattern adjustably connected therewith, said pattern being provided with a visible copying-form, and comprising spacing-numerals to coöperate with the letter-spacing scale, an index-pointer coacting with said pattern and means for turning said pattern simultaneously with the platen.

2. In a type-writing machine, the combination with the platen, of a pattern movable therewith, said pattern having a visible surface, provided with a printed form comprising spacing-numerals, coöperating with the letter-spacing indicator and an index-pointer coacting with the pattern.

3. In a type-writing machine, the combination with the platen, of a pattern arranged on the platen and movable therewith, said pattern having a visible surface provided with a copying-form, comprising spacing-numerals coöperating with the letter-spacing indicator and an index-pointer coacting with the pattern.

4. In a type-writing machine, the combination with the platen, of a pattern-roller movable therewith and a pattern situated on said roller, said pattern having a visible surface provided with a copying-form comprising spacing-numerals coöperating with the letter-spacing indicator, and an index-pointer coacting with the pattern, and means for

turning the pattern simultaneously with and independently from the platen of the type-writing machine.

5. In a type-writing machine, the combination with the platen, of a pattern-roller movable therewith, an exchangeable cylinder mounted on said pattern-roller, means for fixing the cylinder upon this roller, a pattern mounted on the exchangeable cylinder, said pattern having a visible surface provided with the copying-form comprising spacing-numerals coöperating with the letter-spacing indicator, an index-pointer coacting with the pattern, and means for turning the pattern-roller simultaneously with and independently from the platen of the type-writing machine.

6. In a type-writing machine, the combination with the platen, of a pattern-roller axially arranged to the platen and movable therewith, a pattern mounted on said pattern-roller, said pattern having a visible surface provided with a copying-form, comprising spacing-numerals coöperating with the letter-spacing indicator and an index-pointer coacting with the pattern.

7. In a type-writing machine, the combination with the platen, of a pattern-roller detachably secured to the axle of the platen, a pattern carried by the pattern-roller, said pattern having a visible surface provided with a copying-form, comprising spacing-numerals coöperating with the letter-spacing indicator, an index-pointer coacting with the pattern, and means for turning the pattern-roller and the pattern simultaneously with the platen.

8. In a type-writing machine, the combination with the platen, of a pattern-roller detachably secured to the axle of the platen, a spiral pattern carried by the pattern-roller, said pattern having a visible surface provided with a copying-form, comprising spacing-numerals coöperating with the letter-spacing indicator, an index-pointer coacting with the pattern and means for turning the pattern-roller and the pattern simultaneously with the platen.

In witness whereof I have hereunto set my hand in the presence of two witnesses.

RUDOLF VON SOTHEN.
